(57) CLAIM

The ornamental designs for an interior lighting fixture, as shown and described.

DESCRIPTION

FIG. 1 is a top, left end, right side isometric view of a first embodiment of an interior lighting fixture embodying my new design;

FIG. 2 is a top view thereof;

FIG. 3 is a left end view thereof;

FIG. 4 is a right end view thereof;

FIG. 5 is a front side view thereof, the rear side view being a mirror image;

FIG. 6 is a bottom view thereof;

FIG. 7 is a top, left end, right side isometric view of a second embodiment of an interior lighting figure embodying my new design;

FIG. 8 is a top view of FIG. 7;

FIG. 9 is a left end view of FIG. 8, the right end view being identical thereto;

FIG. 10 is a front side view of FIG. 7, the rear side view being identical thereto; and,

FIG. 11 is a bottom view of FIG. 7.
